UNITED STATES PATENT OFFICE.

WESLEY F. HALL, OF LYNN, MASSACHUSETTS.

UNDER-WATER EXHAUST AND MUFFLER.

1,069,945.

Specification of Letters Patent. Patented Aug. 12, 1913.

Application filed April 3, 1912. Serial No. 688,266.

To all whom it may concern:

Be it known that I, WESLEY F. HALL, of Lynn, in the county of Essex and State of Massachusetts, have invented certain new and useful Improvements in Under-Water Exhausts and Mufflers, of which the following is a specification.

My invention has reference to improvements in under-water exhausts and mufflers.

10 The objects of my invention are to provide a simple and efficient under-water exhaust and muffler which is particularly adapted for use in connection with marine engines of the explosion, expansion or similar types, by which the exhaust may be effectively muffled and discharged; and which prevents the exhaust from thumping the hull of the boat.

Other objects of the invention will appear 20 from the following description.

The invention consists in such novel features of construction and combinations of parts as shall hereinafter be fully described and pointed out in the claims.

25 Referring to the drawings:—Figure 1 represents a side elevation of an exhaust and muffler, embodying my invention, attached to the hull of a boat, the portion of the hull shown being in section. Fig. 2 represents an end elevation of the same, with the portion of the hull shown in section. Fig. 3 represents a top plan view of the exhaust and muffler. Fig. 4 represents a sectional view on the line 4—4 of Fig. 1. Fig. 5 represents a sectional view on the line 5—5 of Fig. 1, part of which is broken away to save space. Fig. 6 represents a sectional view on the line 6—6 of Fig. 1. Fig. 7 represents a sectional view on the line 7—7 of Fig. 1. Fig. 8 represents a sectional view on the line 8—8 of Fig. 3.

Like numbers of reference designate corresponding parts throughout.

The preferred form of my invention may 45 be made in one casting, having an elongated base plate 10 which is positioned longitudinally or fore and aft on the bottom of the boat hull 11 and secured thereto in any suitable manner, *e. g.*, by bolts and nuts 12. 50 Projecting from the top and centrally located near the forward end of said base plate is a vertical pipe 13, which extends through the hull 11. The upper end of said pipe is internally threaded, so that it may be 55 connected to the discharge pipe of the engine in a manner well known to those skilled

in the art. Extending through, and downwardly and rearwardly from said base plate is a passage 14 which is a continuation of the passage in the pipe 13. The passage 14 leads into a comparatively wide and low horizontal passage 15. The rear wall of said latter passage has vertical openings 16 which are alternately of the shape of an upright and inverted **U**. Continuations of 60 said openings are elongated horizontal passages 17, which for a portion 17^a of their length in cross section are of the same shape and size as said openings. Each inverted **U**-shaped passage is bounded by side walls 18 65 and a top wall 19 which are integral, there being no bottom wall. Each upright **U**-shaped passage 17 is bounded by the side walls 18 and a bottom wall 20 which are also integral, and said passages open at their 70 top into a water passage 25, hereinafter described. From the foregoing and in Figs. 6 and 7, it is shown that the walls of the passage 17 are integral and are in the form of a corrugated plate, each passage forming a 80 corrugation. The outer walls of each of the outside passages extend uprightly to the under surface of the base plate 10. The rear edges 21 of said walls extend rearwardly and upwardly from the under sides of the 85 portions 17^a of said passage to the under surface of the base plate 10, and in the same inclined plane, the rear edges 22 of the remaining passages extend from the under side of the portions 17^a to the top wall of 90 said passages.

Adjacent to the starboard and port sides of the walls of the passage 14, are passages 23 and 24, respectively, the forward ends of which are open. Said latter passages 95 lead into the comparatively low passage 25, of which the top wall is a portion of the base plate 10, and the vertical side walls are the continuations of the two outer vertical side walls of the passages 17. The rear end 100 of the passage 25 is open.

By the forward movement of the boat, a continuous stream of water is forced through each of the passages 23 and 24 which join into a single stream in the passage 105 25. Said stream continues moving from the rear opening of the passage 25 toward the rear end of the boat. The rapidity of said stream and the distance it moves from the passage 25 toward said end of the boat varies in proportion to the speed of said boat.

110 The discharge from the exhaust pipe of

the engine passes through the pipe 13, the passage 14, the passage 15, and the openings 16, into the U-shaped discharge passages 17. A small portion of the discharge 5 in the upright U-shaped passages will enter the stream in the passage 25, and the remainder will pass through the rear openings in said upright U-shaped passages. The portion of the discharge which enters the 10 passage 25 will vary with the speed of the boat. A portion of the discharge in the inverted U-shaped passages will pass into the water below said passages and the remainder will pass out through the rear openings 15 in said passages. The portion of the discharge which will pass into the water below said passages will vary with the speed of the boat. The stream of water, which passes through the passage 25 and continues moving toward the rear end of the boat, forms 20 a barrier to prevent the discharge from thumping the hull of the boat. The movement of the boat will tend to prevent water from entering the passages 17, so that the discharge will have a substantially free passage therein.

It is evident from the foregoing that the discharge enters the water through several different openings and in several different 30 directions; this is an important feature of my invention, for the reason that in under-water exhausts heretofore invented, as far as I am aware, the discharge enters the water in one volume, and there is nothing 35 to prevent it from thumping the hull of the boat, which causes considerable vibration and noise.

Having thus described my invention I claim as new and desire to secure by Letters Patent:—

- 40 1. In an under-water exhaust and muffler the combination of a discharge passage with a water passage located above said discharge passage.
- 45 2. In an under-water exhaust and muffler the combination of a rearwardly and upwardly opening discharge passage with a water passage located above said discharge passage.
- 50 3. In an under-water exhaust and muffler the combination of a rearwardly and downwardly opening discharge passage with a water passage located above said discharge passage.
- 55 4. In an under-water exhaust and muffler the combination of a rearwardly, upwardly and downwardly opening discharge passage with a water passage located above said discharge passage.
- 60 5. In an under-water exhaust and muffler the combination of a plurality of discharge passages with a water passage located above said discharge passages.
- 65 6. In an under-water exhaust and muffler the combination of a plurality of rearwardly

and upwardly opening discharge passages with a water passage located above said discharge passages.

7. In an under-water exhaust and muffler the combination of a plurality of rearwardly and downwardly opening discharge passages 70 with a water passage located above said discharge passages.

8. In an under-water exhaust and muffler the combination of a plurality of rearwardly, upwardly and downwardly opening discharge passages with a water passage located above said discharge passages. 75

9. On under-water exhaust and muffler comprising a base plate which is adapted to 80 be attached to the hull of a boat, a vertically extending pipe projecting from said base plate, a passage connecting the passage in said pipe to a comparatively wide and low horizontal passage, and a plurality of discharge passages leading from said horizontal passage. 85

10. In an under-water exhaust and muffler the combination of a base plate which is adapted to be attached to the hull of a boat, 90 a vertically extending pipe projecting from said base plate, a passage connecting the passage in said pipe with a comparatively low and horizontal passage, a plurality of discharge openings in the rear wall of said 95 horizontal passage, with a water passage located above said horizontal passage.

11. An under-water exhaust and muffler made in one casting, comprising a base plate which is adapted to be attached to the hull 100 of a boat, a vertically extending pipe projecting from said base plate, which is adapted to be attached to the exhaust pipe of the engine, a downwardly and rearwardly extending passage which leads from the passage in said pipe to a comparatively wide and low horizontal passage, a plurality of inverted U-shaped discharge passages and a plurality of upright U-shaped discharge 105 passages leading from said horizontal passage, said inverted U-shaped passages opening rearwardly and downwardly, and said upright U-shaped passages opening rearwardly and upwardly. 110

12. An under-water exhaust and muffler 115 comprising a base plate, a vertically extending pipe projecting from said base plate, a downwardly and rearwardly extending passage leading from the passage in said pipe to a horizontal passage, a discharge passage 120 or passages leading from said horizontal passage, a passage on the starboard and port sides of the walls of said downwardly and rearwardly extending passage, having their forward ends open, and having their rear 125 ends opening into a comparatively wide and low passage having its rear end open, said lateral passage located above said first-mentioned horizontal passage.

13. An under-water exhaust and muffler 130

comprising a single casting provided with a base plate, a vertically extending pipe projecting from said base plate, a downwardly and rearwardly extending passage leading 5 from the passage in said pipe to a comparatively wide and low horizontal passage, a plurality of horizontal discharge passages in the form of a corrugated plate leading from said horizontal passage, a passage on 10 the starboard and port sides of the wall of said downwardly and rearwardly extending passage having their forward ends open and their rear ends opening into a compara-

tively wide and low horizontal passage which opens rearwardly, said latter passage 15 extending above and adjacent said first mentioned horizontal passage and said discharge passage, all substantially as and for the purpose set forth.

In testimony whereof I have affixed my 20 signature, in presence of two witnesses.

WESLEY F. HALL.
